US00D894270S

(12) **United States Design Patent** (10) **Patent No.:** **US D894,270 S**
(45) **Date of Patent:** **** Aug. 25, 2020**

(54) **MEDIA PROCESSING DEVICE**

(71) Applicant: **ZEBRA TECHNOLOGIES CORPORATION**, Lincolnshire, IL (US)

(72) Inventors: **Konstantinos Tsipanatos**, Selden, NY (US); **JaeHo Choi**, Whitestone, NY (US); **Sunghun Lim**, Bethpage, NY (US); **Curt D. Croley**, Stony Brook, NY (US)

(73) Assignee: **Zebra Technologies Corporation**, Lincolnshire, IL (US)

(**) Term: **15 Years**

(21) Appl. No.: **29/690,678**

(22) Filed: **May 9, 2019**

Related U.S. Application Data

(62) Division of application No. 29/609,961, filed on Jul. 7, 2017, now Pat. No. Des. 854,079.

Assistant Examiner — J. Thorn, Sr.

CLAIM

We claim the ornamental design for a media processing device, as shown and described.

DESCRIPTION

FIG. 1 is a first perspective view of a media processing device;

FIG. 2 is a second perspective view thereof;

FIG. 3 is a first side view thereof;

FIG. 4 is a second side view thereof;

FIG. 5 is a top view thereof;

FIG. 6 is a bottom view thereof;

FIG. 7 is a front view thereof; and,

FIG. 8 is a rear view thereof.

The broken lines shown in the drawings depict portions of the media processing device that form no part of the claimed design.
